[57] CLAIM

The ornamental design for a boat hull, as shown and
described.

DESCRIPTION

FIG. 1 is a bottom plan view of a boat hull showing my
new design;

FIG. 2 is a right side elevational view thereof, the left
side elevational view being a mirror image of that
shown;

FIG. 3 is a front elevational view thereof; and,

FIG. 4 is a rear elevational view thereof.

FIG. 3

FIG. 4
